(57) **CLAIM**

The ornamental design for a canister, as shown and described.

DESCRIPTION

FIG. 1 is a rear/left/bottom perspective view of a first embodiment of the canister (a rear/right/bottom perspective view would be a mirror image thereof);

FIG. 2 is a front/right/top perspective view thereof (a front/left/top perspective view would be a mirror image thereof);

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof; and

FIG. 8 is a bottom plan view thereof.

FIG. 9 is a rear/left/bottom perspective view of a second embodiment of the canister (a rear/right/bottom perspective view would be a mirror image thereof);

FIG. 10 is a front/right/top perspective view thereof (a front/left/top perspective view would be a mirror image thereof);

FIG. 11 is a front elevational view thereof;

FIG. 12 is a rear elevational view thereof;

FIG. 13 is a left-side elevational view thereof;

FIG. 14 is a right-side elevational view thereof;

FIG. 15 is a top plan view thereof; and

FIG. 16 is a bottom plan view thereof.

FIG. 17 is a rear/left/bottom perspective view of a third embodiment of the canister (a rear/right/bottom perspective view would be a mirror image thereof);

FIG. 18 is a front/right/top perspective view thereof (a front/left/top perspective view would be a mirror image thereof);

FIG. 19 is a front elevational view thereof;

FIG. 20 is a rear elevational view thereof;

FIG. 21 is a left-side elevational view thereof;

FIG. 22 is a right-side elevational view thereof;

(Continued)

FIG. 23 is a top plan view thereof; and,
 FIG. 24 is a bottom plan view thereof.
 The dash-dot broken lines show the bounds of the invention
 and form no part of the claimed design. The other uniformly
 broken lines show portions of the canister that form no part
 of the claimed design.
